FILAMENT SUPPORT

William W. Eitel and Jack McCullough, San Bruno, Calif., assignors to Heintz & Kaufman, Ltd., San Francisco, Calif., a corporation of Nevada

Application December 11, 1933, Serial No. 701,757

5 Claims. (Cl. 176—39)

Our invention relates to the support of filaments in lamps and like devices.

One of the objects of our invention is the provision of a unitary structure for the support of 5 multiple filaments.

A further object of our invention is to provide improved means for supporting filaments operated in parallel.

Another object of our invention is the provision of a filament support which is easily assembled in devices of the character described.

Still another object of our invention is the provision of a filament support which may be adjusted, at assembly to accommodate variations 15 in the lengths of the filaments.

Another object of our invention is the provision of an improved method of supporting filaments.

Other objects of our invention will be apparent 20 or will be specifically pointed out in the description forming a part of this specification, but we do not limit ourselves to the embodiment of the invention herein described, as various forms may be adopted within the scope of the 25 claims.

Referring to the drawing:

Figure 1 is a front elevation of a lamp embodying our invention. Portions are omitted to shorten the view and portions are broken away 30 to disclose the interior construction.

Figure 2 is an elevational view of the doubled filament support before forming.

Figure 3 is an elevational view of the filament support after forming.

35 The device of our invention is adapted for use in lamps, thermionic devices and the like which are provided with hairpin type filaments, operated in parallel, and a standard placed adjacent the filament. It comprises, broadly, a ferrule, 40 preferably constructed of wire, which is adapted to be slidably secured on the standard and is provided with arms which have means thereon for engaging the bights of the filaments.

In the art of lamp manufacture, the need has 45 been felt for a sturdy, yet easily constructed and applied, filament support. The supports in present use are, for the most part, delicate and difficult to construct and hence provide an impediment to the efficient production of these 50 devices. We have provided a support which is simple, rugged and easy to construct and, by means of which, the manufacturing time on lamps and like devices is materially reduced.

In greater detail, referring to Figure 1, our 55 invention is illustrated as being incorporated in

a lamp comprising an envelope 2 provided with the usual stem 3. A central metallic standard 4 is provided, suitably secured in the "pinch" of the stem, and located, preferably, between the filament leads 6 similarly secured in the stem. 5

The filaments 7 are of the hairpin type and are shown as being connected to the leads 6 through the medium of U shaped bars 8. The filaments are, preferably, connected in parallel. It will be understood that we do not limit ourselves to this particular construction as a wide variety of arrangements for the filaments may be employed.

10 The filament support, generally indicated by the numeral 9 of Figure 1, is best illustrated in detail in Figures 2 and 3. A piece of wire, of suitable length, is bent to provide a double rod 11 having a joined or looped end 12 and an open end 13. Hooks 14 are formed at the free end of the wires.

15 The rod 11, starting at the looped end 12, is wound on a mandrel, of suitable diameter, to provide a ferrule 16 which is slidable on the standard 4. The free ends of the wire are led out tangentially, and in opposite directions, 20 from the ferrule and are bent back at 17 to provide resilient arms 18. In their final position the hooks 14 lie substantially diametrically opposite each other.

25 The support is now ready for assembly. The ferrule 16 is placed on the standard 4 and the bights 19, of the filaments, are disposed in the hooks 14. The ferrule is now moved upwardly, to properly tension the filaments, and secured in position, preferably by means of welding, as 30 at 21.

35 It has been found that, by using the filament support of our invention, the production time on lamps and vacuum tubes has been reduced considerably due to the ease with which it is assembled into these devices and the fact that the operator has but a single piece to handle. Since, due to the parallel arrangement of the filaments, there is no difference of potential between the bight thereof, the use of a conducting 40 support does not affect their operation.

45 We claim:

1. In an envelope containing a pair of hairpin shaped filaments and a standard disposed adjacent the filament, a filament support comprising a pair of parallel wires joined at one end and having a portion thereof including the joined ends coiled about the standard, and means at the free ends thereof for engaging the bights of the filaments. 50

2. In an envelope containing a pair of hairpin shaped filaments and a standard disposed adjacent the filament, a filament support comprising a pair of parallel wires joined at one end and having a portion thereof including the joined ends coiled about the standard, the free ends thereof extending from said coiled portion to provide arms, and means on the arms for engaging the bights of the filaments.
- 10 3. In an envelope containing a pair of hairpin shaped filaments and a standard disposed adjacent the filament, a filament support comprising a pair of parallel wires joined at one end and having a portion thereof including the joined ends coiled about the standard, to provide a ferrule slideable thereon, the free ends of said wires extending from the ferrule portion to provide resilient arms, and having hooks formed thereon for engaging the bights of the filaments.
- 15 4. The method of supporting filaments in an envelope containing a hairpin shaped pair of said filaments and a standard disposed adjacent

the filaments, which comprises bending a length of wire to double it, closely winding that portion of the doubled wire adjacent the bend about the standard, and providing the free ends of the wire with means for engaging the bights of the filaments.

5. The method of supporting filaments in an envelope containing a hairpin shaped pair of said filaments and a standard disposed adjacent the filaments, which comprises bending a length of wire to double it, closely winding that portion of the doubled wire adjacent the bend about the standard, to provide a ferrule slideable thereon, bending the free ends of the wire outwardly to provide resilient arms, forming hooks at the ends of the arms to engage the bights of the filaments, sliding the ferrule on the standard to obtain suitable tension in the springs, and welding the ferrule to the standard.
